UNITED STATES PATENT OFFICE.

PAUL VIET, OF BILLANCOURT, FRANCE.

STARTING ARRANGEMENT FOR INTERNAL-COMBUSTION ENGINES.

Application filed February 6, 1926, Serial No. 86,641, and in France September 3, 1925.

The present invention relates to a starting arrangement for internal combustion engines, and more particularly to means for supplying such engines with air carburetted with petrol (or any other carburetted liquid or gas) which is taken from a small auxiliary internal combustion engine during the compression period, said auxiliary engine utilizing for its normal operation the same carburetted air.

The specification and the annexed drawings show various constructions of arrangements according to the invention.

In the accompanying drawings:

15 Fig. 1 is a diagrammatic section of the auxiliary starting engine.

Figs. 2 and 3 show two constructions of a device for re-carburetting the carburetted mixture before its admission to the engine to be started.

Figs. 4, 5 and 6 show different positions of the cock which serves for connecting the bodies of the carburetter and the atomizer shown in Figs. 2 and 3.

25 Fig. 7 is a view in elevation showing the connection of the auxiliary starting motor to an internal combustion engine.

Fig. 1 shows in diagrammatic section the device which comprises a small auxiliary ordinary four-cycle motor 1, having in addition to the admission valve 2 which may be either positively operated or automatic, and the discharge valve 3, a third controlled valve 4, the stem of which has been packed tight by means of a suitable packing device 5, for instance, a packing gland. This valve enables the carburetted air, used for the normal operation of the auxiliary engine 1 (whilst same is in the compression period) to pass into a

40 port 6, the capacity of which is made as small as possible and which is closed by an automatic valve 7 loaded by means of a spring 8 which may be regulated for instance by means of a screw cap 9. The valve 7 connects in its open position the port 6 with a pipe 10 leading to the engine to be started.

The operation of this arrangement is as follows:

The auxiliary engine 1 is designed to have 50 a compression chamber of smaller volume than usual, which enables the carburetted explosive mixture to be compressed to the highest possible degree (6 to 10 kgs. for instance); when the piston moves towards the end of its upward stroke, the valve 4 is low-

ered, but the loaded valve 7 cannot rise until the degree of compression has exceeded a certain value determined by the spring 8, the final compression being at least 3 kgs. for instance, for the operation of the auxiliary 60 engine.

The communication with the pipe 10 leading to the engine to be started, which has been established by the valve 7, enables the excess pressure to pass away, and the valve 4 closes 65 after the explosion. At each compression in the auxiliary engine, a portion of the carburetted mixture will therefore enter the engine to be started until the maximum degree of compression in the latter is reached. An 70 electric spark, which may be produced by a storage battery or a starting magneto, will thus suffice for starting the engine to be started. In case a mis-timed ignition should take place owing to the high degree of compression, no damage would be caused thereby, 75 and the engine would merely start automatically.

In Figure 7 is shown the auxiliary motor 1 connected by its outlet pipe 10 and the pipe 80 27 to the carburetter 12 and from such carburetter by the pipe 28 to the intake of the motor 29 to be started.

Where it is not desired to re-carburet the mixture for the engine to be started the outlet pipe 10 can be connected directly to the engine.

In the example just described it was assumed that a four-cycle engine would be used, but a two-cycle engine, with or without auxiliary compression cylinders, could be used equally well. A suitable controlling-valve may also be used instead of the screw-cap 9 and spring 8.

It must, however, be observed that the normal carburetted mixture supplied by the pipe 10, meets a large amount of pure air in the cylinders of the engine to be started and in the admission pipe; it is therefore rendered lean and it is advisable to re-carburet same 100 to the normal degree, if faulty starting is to be avoided, though the engine may be started under circumstances with the mixture of the auxiliary engine, without any re-carbureting arrangement.

For this purpose, a simple atomizer as shown in Fig. 2 or a double atomizer as shown in Fig. 3 may be added to the carburetter 11 of the auxiliary engine 1.

According to Fig. 2, the carburetter 11 is 110

in communication with the atomizer 12 by means of a cock 13. The mixture to be re-carburetted enters through an opening 14 into the chamber of the atomizer 12. The 5 pressure acting upon the free surface of the liquid forces the latter to pass into the simple sprayer 15 and then atomizes the liquid in the gaseous current passing around the sprayer, before passing the normally saturated mixture to the engine to be started through pipe 16. The charging of the carburettor 11 of the auxiliary engine 1 and the atomizer 12 of the engine to be started may be accomplished by means of a plug 17. The 10 cock 13 enables the two reservoirs 11^a and 12^a to be brought into communication during the charging and to be separate from one another during starting, so as to make the reservoir 11^a of the atomizer 11 pressure-tight. The charging might also be effected by means of an additional pump or a charging reservoir.

In the re-carburetting arrangement according to Fig. 3 a carburettor 11 of the auxiliary engine is connected to a double sprayer 18, which as in the previous case is entered by the mixture to be re-carburetted through an opening 19. The pressure present in the sprayer forces the carburetting liquid to pass into the sprayer 20; this liquid is then atomized in the atomizer 21 by the gaseous current passing around the sprayer 20. A branch passage of the compressed gaseous mixture provided with a valve 22 loaded by a spring 23, causes said mixture to open the valve 22 in expanding, and effects the spraying and the normal carburation of the re-carburetted mixture before the latter passes to the engine to be started.

40 The reservoirs 11^a of the carburettor and 18^a of the sprayer communicate with each other through a cock 24, to the plug of which the carburetting liquid is admitted by a pipe 25 (see Fig. 5). This cock 24 may assume three different positions:

1. The position according to Fig. 4 which permits air in the reservoir 18^a to escape through pipe 26.

2. The position according to Fig. 6 in which the reservoirs 11^a and 18^a are in communication.

3. A closing position not shown, which during the starting period causes the previously mentioned openings to be closed so as

to render the reservoir 18^a absolutely tight, 55 and prevent pressure entering through the openings 19 from being transmitted for instance to the charging reservoir, and avoiding bursting of the latter.

Claims:

1. A starting device for internal combustion engines comprising an auxiliary internal combustion engine, said engine being provided with fuel intake and exhaust valves, a carburetor in communication with said intake valve, a conduit connecting said auxiliary engine with the engine to be started, a pressure operated valve in said conduit operable to open position through pressure in auxiliary engine only, and means for regulating the opening of said pressure operated valve to permit escape of a portion of the carburetted air in said auxiliary engine to said passage when a predetermined pressure in said auxiliary engine has been reached. 70

2. A starting device for internal combustion engines comprising an auxiliary internal combustion engine, said engine being provided with fuel intake and exhaust valves, a carburetor in communication with said intake valve, a conduit connecting said auxiliary engine with the engine to be started, a third valve in said conduit, means for regulating the opening of said third valve to permit escape of a portion of the carburetted air in said auxiliary engine to said passage, and a second carburetor interposed in said passage for further carburetting the mixture supplied to the engine to be started.

3. A starting device for internal combustion engines comprising an auxiliary internal combustion engine, said engine being provided with fuel intake and exhaust valves, a carburetor in communication with said intake valve, a conduit connecting said auxiliary engine with the engine to be started, a pair of valves in said conduit, a cam shaft, means on said cam shaft for controlling said intake and discharge valves and one of said pair of valves, and spring regulated means for controlling the other of said pair of valves to permit said other valve to open when a predetermined pressure in said auxiliary engine has been reached. 100

In testimony whereof I hereunto affix my 105 signature.

PAUL VIET.
